UNITED STATES PATENT OFFICE.

LEE HALL, OF CHICAGO, ILLINOIS, ASSIGNOR TO FEDERAL ELECTRIC COMPANY, INC., OF CHICAGO, ILLINOIS, A CORPORATION OF NEW YORK.

SIGN.

Application filed March 8, 1926. Serial No. 93,059.

This invention relates to improvements in signs, and consists of the matters herein-after described and more particularly pointed out in the appended claims.

5 The invention relates to roof signs and other signs of the kind, wherein skeleton letters are used,—the said letters being supported upon and secured to a frame structure including the usual parallel vertically spaced bars, to which the latters are attached.

The present invention relates more particularly to the mountings or attachments, by means of which, the skeleton letters are secured to the said bars of the structure, and

15 the object of the invention is to provide a mounting of the kind which is of cheap and economical construction, which enables the letters to be readily and quickly erected and changed when desired, and which will be

20 hidden from the view of the observer in front of the sign.

The advantages of the invention will appear more clearly as I proceed with the specification.

25 In the drawings:—

Figure 1 is a view in front elevation showing a skeleton letter mounted upon the bars of a structure such as is used in roof signs or other signs of the kind.

30 Figure 2 is a view representing a vertical section through Figure 1 in a plane indicated by the line 2—2 thereof.

Figure 3 is a view representing, upon a somewhat enlarged scale, and in perspective, 35 one of the mountings attached to a bar of the sign supporting structure, with the skeleton letter eliminated.

Figure 4 is a view representing a rear elevation of Figure 1.

40 Figure 5 is a view representing on an enlarged scale a horizontal section through Figure 4 in a plane indicated by the line 5—5 of Figure 4.

45 Referring now to that embodiment of the invention illustrated in the drawing:—10, 10 indicate spaced horizontal bars, in this case, angle bars, which form a part of the familiar open frame structure by which a roof or the like sign is supported. 11 indicates a skeleton letter which may be of any familiar or usual construction. Said letter is mounted in erect position on the two bars 10, 10 with its back 12 attached to the bars 10, 10, by the mountings or attachments 13,

Each mounting 13 consists of the following:—14 indicates a clip which is rigidly attached to the back 12 of the letter. Said clip has a base 15 provided with screw holes to receive screws for attaching it to the back 10 12 of the letter and a tongue 16 which is offset rearwardly from the plane of the base 15. 17 indicates a U-bolt which is adapted to be engaged in the space between the tongue 16 and the back 12 of the letter. 18 indicates a clamping plate apertured to receive the side legs 17^a, 17^b of the U-bolt, and 19, 19 indicate clamping nuts threaded upon said legs 17^a, 17^b.

70 The clips 14 may be attached to the backs of the skeleton letters when they are shipped for erection or may be attached at the place of erection. A plurality of said clips are provided for each letter, depending upon the size and form of the letter. As for example, 75 the letter "I" would usually require but two mountings, while a letter such as "F" would require 3, and in the case of an "E", there would be preferably 4 such mountings. The letter is placed with its back toward the bars 80

10, 10 and the U-bolts 17 are engaged upon the several bars 10, as shown in the drawings. The clamping plate is then applied to the legs 17^a, 17^b of the U-bolt and the nuts 19 are drawn up against the clamping plate 85

18 to securely draw the tongue 16 of the clip 14 against the face of the bar 10. Where angle bars are used in the supporting structure, as in the case illustrated, a spacing sleeve 20 is used on the leg 17^b between the 90 clamping plate 18 and the vertical flange of the angle bar to take up the space between said flange and the clamping plate. Manifestly where channel bars are used, no such sleeve would be required. When the clamping plates 18 of the several mountings used with a letter are drawn up as described, the said letter will be securely and fixedly attached to the bars 10 of the sign structure.

95 To obviate any danger of disengagement 100 of the tongue of the clip 14 from the U-bolt 17, said tongue is provided with a hook 17^c at its end to act as a stop to lock the hook against withdrawal from beneath the head of the U-bolt. Thus, in case the clamping plate is not drawn up sufficiently tight to prevent relative movement between the tongue of the clip and the head of the U-bolt, lateral movement of the letter under 105 wind pressure or other force, will be arrested 110

in one direction by the shoulder 16^b adjacent the base 14 and in the other direction by the hook 17^c.

The advantages of the invention will be manifest to those familiar with the art. The U-bolts may be loosely adjusted on the bars in the proximate required location preliminary to the actual erection of the letters. Then, the letters may be placed against the bars and the clips engaged between the heads of the U-bolt and the bars as illustrated in Figure 3, after which the nuts 19 may be drawn up to rigidly clamp the clips to the bars. The letters may be taken down and changed or renewed with equal facility. The U-bolts and clips remain on the bars ready for the attachment of other letters (such as are not required being readily removable) and in case additional ones are required, on account of the different letter used to occupy the same space, they may be added as desired.

It will be noted from an examination of Figure 1 and Figure 4 that the mountings 13 are entirely hidden from view by an observer in front of the letter, said mountings being disposed at the back of the letter and well within the vertical and horizontal dimensions of the parts of the letters to which they are attached.

I claim as my invention:—

1. In a sign structure, in combination with a supporting bar thereon and a skeleton letter erected on said supporting structure, a clip fixed to the back of said skeleton letter, said clip comprising a base attached to said letter back and a tongue offset from said base and extending parallel thereto, a U-bolt engaged on said tongue and straddling said bar, a clamping plate engaged upon said U-bolt, and clamping nuts for clamping said plate and tongue in rigid engagement with said bar.

2. In a sign structure, in combination with a supporting bar thereon and a skeleton letter erected on said supporting structure, a

clip fixed to the back of said skeleton letter, said clip comprising a base attached to said letter back and a tongue offset from said base, extending parallel thereto and having a hook at its end, a U-bolt engaged on said tongue and straddling said bar, a clamping plate engaged upon said U-bolt, and clamping nuts for clamping said plate and said tongue in rigid engagement with said bar. 50

3. In a sign structure, in combination with a supporting angle bar thereon and a skeleton letter erected on said supporting structure, a clip fixed to the back of said skeleton letter, said clip comprising a base attached to said letter back and a tongue offset from said base and extending parallel thereto, a U-bolt engaged on said tongue and straddling said bar, a clamping plate engaged upon said U-bolt, and clamping nuts for clamping said plate and tongue in rigid engagement with said bar, and a spacing sleeve on one leg of said U-bolt between said clamping plate and said angle bar. 60

4. A mounting for skeleton sign letters comprising a clip adapted for attachment to the back of a letter, said clip comprising a base and a tongue offset from said base and extending parallel thereto, a supporting bar, a U-bolt adapted for engagement upon said tongue and bar, a clamping plate engaged upon said U-bolt, and clamping nuts on said U-bolt. 70

5. A mounting for skeleton sign letters comprising a clip adapted for attachment to the back of a letter, said clip comprising a base and a tongue offset from said base and extending parallel thereto, said tongue having a hook at its end, a supporting bar, a U-bolt adapted for engagement upon said tongue and bar, a clamping plate engaged upon said U-bolt, and clamping nuts on said U-bolt. 80

In testimony that I claim the foregoing as my invention, I affix my signature this 2d day of March, 1926. 90

LEE HALL.
